UNITED STATES PATENT OFFICE.

HENRY SEHER, OF NEW YORK, N. Y.

DEVICE FOR FASTENING SLIP-COVERS ON UPHOLSTERED FURNITURE.

SPECIFICATION forming part of Letters Patent No. 517,306, dated March 27, 1894.

Application filed August 7, 1893. Serial No. 482,548. (No model.)

To all whom it may concern:

Be it known that I, HENRY SEHER, of the city, county, and State of New York, have invented certain new and useful Improvements 5 in Devices for Fastening Slip-Covers on Upholstered Furniture, of which the following is a full, clear, and exact description.

My invention is applicable to slip covers such as are used on upholstered furniture to 10 protect it from dust, and the object of the invention is to provide means whereby such covers may be firmly and smoothly held on the furniture and especially on the seat thereof, to prevent the cover from assuming an untidy appearance.

To these ends, my invention consists of 15 novel devices for firmly holding the slip cover down on the seat, back or other part of upholstered furniture, the said fastening devices being located at or along the edge of the seat, back, or other part. Where the cushions 20 of two such parts meet, I employ spring fasteners that are adapted to be forced, with the slip cover, into the crease between the 25 said cushions. The spring fasteners are held on a rod.

The invention will now be described specifically with reference to the accompanying drawings, and the features of novelty pointed 30 out in the claims.

Figure 1 is a perspective view of a chair provided with a slip cover and fastening devices applied thereto according to my invention, the slip cover being lifted from one of 35 the arms to show the manner of securing the cover to the seat at the side. On the seat I have shown the rod with the fasteners ready for insertion between the seat and the back. Fig. 2 is a sectional elevation of an armless 40 chair, the rod with the fasteners being in position. Fig. 3 is an enlarged sectional detail view of the back, the seat and the rod with the fasteners in position between the back and the seat. Fig. 4 represents the rod with 45 the fasteners thereon, the end of the rod being curved. Fig. 5 is an enlarged detail view of one of the fastening pins I shown in Fig. 1 as a means for securing the slip cover to the side of the seat. Fig. 6 shows the same pin 50 with an ornamental ball attached thereto; and Fig. 7 is a detail view of one of the fasteners.

Like letters refer to corresponding parts throughout the several views.

In Figs. 1, 2, and 3, A indicates the cushion of the seat, and B that of the back.

C is the slip cover, the portion C' whereof is adapted to cover the seat, while the portion C² covers the back, and the side portions C³ cover the arms. The cushions A and B are in contact with one another in the chair illustrated by the drawings, but at the sides there is an opening between the arms D and the seat, so that the side edges of the seat A are freely accessible from the outside.

In order to fasten the slip cover C in the 65 crease between the seat A and the back B, I employ the fastener or hold-fast E, shown in detail in Fig. 7. The fastener is made of an elastic material, preferably sheet brass, steel or another suitable metal, and is composed, 70 as illustrated, of a curved central portion E' and parallel or diverging arms E². The ends of the said arms are bent outwardly, as shown at E³, and the edges at the ends of the arms are provided with teeth or corrugations E⁴. 75 Preferably the fasteners are loosely held on a rod F (see Fig. 4), and a screw G, in conjunction with a nut H, serves to prevent the rod from slipping out from between the fasteners when the same are in position. The 80 arms E² of the fasteners E are preferably provided with apertures E⁵. It will be obvious that the spring power of the fastener will tend to keep the arms E² in a diverging position. The rod F to be used for a chair of the type 85 shown in the drawings would be straight, extending only to the point marked F' in Fig. 4. The fasteners E are slid over the rod so that the latter lies between the central portions E' of the fasteners and the screws G. 90 The slip cover C being in position, the rod F with the fasteners E is brought near the crease between the back and the seat, as shown in Fig. 1, the central portion of the fastener being adjacent to the crease. Then the 95 rod with the fasteners is forced in between the back and the seat, into the position shown in Figs. 2 and 3. It will be understood that the spring arms E² of the fasteners are pressed toward one another, but the elasticity of the 100 said arms is sufficient to press the ends or offsets E³ against and into the slip cover to hold

the same firmly against the cushions A and B, and the serrations or teeth E⁴ will increase the hold of the fasteners on the slip cover. When it is desired to remove the fasteners 5 and the rod, a suitable hook is preferably inserted into the apertures E⁵ of the fasteners to withdraw the latter from between the back and the seat.

The rod F is considered a very advantageous feature of my invention since it will 10 keep the fasteners in alignment with each other and thereby exert a uniform strain on the slip cover so as to keep it smooth. Furthermore, by using such a rod, all the fasteners are simultaneously brought into the 15 position shown in Figs. 2 and 3. The nut H may be unscrewed to allow of spreading the arms E² of the fastener to adjust their spring power. When such an adjustment is not required, rivets may be used instead of screws 20 and nuts. It will be further obvious that the above described fasteners E can only be employed where two cushions abut against one another.

25 In order to conceal the fasteners in the crease between the cushions, I provide pins such as shown in Fig. 6, the main parts of the said pin being represented at Fig. 5, and either of the pins illustrated in Figs. 5 and 30 6, may be further employed to fasten the slip cover to the free edge of a cushion, for instance, to the side edges of the seat cushion A of the chair shown in Fig. 1.

I is a coiled spring the ends whereof, I', 35 are abruptly bent inward to extend parallel to one another. The ends I' are pointed and constitute a pair of needles or pins, which overlap each other at their inner ends. A ball J of an ornamental character may be attached to the coiled spring I, as will be seen in Fig. 6. These fastening pins are employed in the following manner to secure the slip cover to the sides of the seat A. The outside flap of the side portion C³ of the slip cover is 40 lifted off the arm D, as illustrated in Fig. 1, then the inside flap of the said side portion and the seat portion C' of the slip cover are drawn forcibly outward to stretch the slip cover smooth on the seat, and the fastening pins I I' 45 are successively passed into the cushion A through the slip cover, to hold the latter in position. One of the ends I' of the fastening pins is first forced into the cushion then the coils of the spring I are drawn apart and when the 50 other end I' of the pin is stuck into the cushion and the pin released, the spring will be automatically contracted and thereby cause the pointed end to fully enter the cushion. It will be obvious that these fastening pins can 55 be disengaged only by a strong lateral pull, and if any slight lateral pull should occur, the coiled spring I will bring the ends I' to their original position as soon as the pull ceases. The fastening pins I I' are preferably 60 provided with ornamental balls J when they are to be used near the crease at the top of the

back (Fig. 1) or at any other place where they are visible. It will be understood that the pins I I' serving to pin the slip cover C to the sides of the seat A in Fig. 1, are normally out 70 of sight, being covered by the outside flap of the portion C³ of the slip cover. The pins provided with ornamental balls (Fig. 6) when fastened on the back near the seat, as indicated in Figs. 2 and 3, will conceal the outer 75 ends of the fasteners E which otherwise might be visible from the front.

It will be understood that the fastening pins may be dispensed with in a chair or other article of furniture in which the arms 80 are provided with cushions that extend down to the seat and virtually form a continuation of the back cushion B. In such a case it will be sufficient to employ fasteners E either on several separate rods F (one rod for the back 85 and one for each side of the seat), or on a single curved rod of the type shown in Fig. 4. It is however preferred to employ pins such as shown in Fig. 6 near the crease formed between two cushions, as illustrated in Figs. 2 90 and 3, in order to conceal the fasteners E located in the crease.

By means of the above described fastening devices, a slip cover can be firmly and smoothly held on furniture, and will remain 95 in position when a person sits down on the chair so that it will not be necessary to rearrange the slip cover each time the chair has been used.

Having thus fully described my invention, 100 I claim as new, and desire to secure by Letters Patent—

1. A device for fastening slip covers on upholstered furniture, the same comprising separate independent fasteners each provided 105 with a tubular portion, and a rod passed loosely through the fasteners to hold them in alignment and allow them to be adjusted relatively to each other, substantially as described. 110

2. A device for fastening slip covers on upholstered furniture, the same comprising a rod and separate fasteners each provided with a tubular portion for the reception of the rod, and a stop located in advance of said 115 tubular portion, for preventing the rod from slipping out from between the fasteners, substantially as described.

3. A device for fastening slip covers on upholstered furniture, the same comprising a 120 rod and separate fasteners each provided with a tubular portion for the reception of the rod, a screw passing through the fastener in front of the said tubular portion, to prevent the rod from slipping out from between 125 the fasteners, and a nut for holding the screw in position, as and for the purpose set forth.

HENRY SEHER.
